ALFRED W. POSEY, OF LONG BEACH, CALIFORNIA, ASSIGNOR OF ONE-HALF TO JAMES M. QUEEN, OF LOS ANGELES, CALIFORNIA

SAFETY DEVICE FOR ROTARY CATHEADS

Application filed December 11, 1924. Serial No. 755,354.

My invention relates to safety devices adapted to be associated with a motor and the rotary member driven thereby, or each individually, so that either or both may be practically instantly stopped under certain conditions. More particularly my invention is adapted to be associated with the rotary cat head, winch, nigger head, or whatever term may be used to designate the rotary element associated with the draw works of a well drilling apparatus, the purpose of my invention being to insure the safety of the operators or individuals present when said draw works is in operation.

As is well known, the rope or line used on the rotary cat head of the draw works of a well drilling apparatus frequently, and without any previous indication thereof, "fouls" or loops or crosses itself, instead of being wound evenly on said cat head. This proceeding, as everyone versed in oil well drilling knows, is very dangerous to the individuals standing close by. It is by no means an uncommon occurrence for such a fouled rope or line to catch the operator, or the individual standing close by, and wind him about the cat head, breaking his arms or legs, and often crushing him to death, sometimes flinging him many feet, which results in his instant death. There are numerous instances on record where this has been done.

By the use of my invention, as has been clearly exemplified in practice, all such dangerous incidents and accidents are entirely avoided and prevented. When my apparatus has been installed, the cat head and the motor associated therewith may be practically instantly stopped, automatically and manually, whenever the rope or line fouls or anything has happened to the machinery.

While my apparatus is particularly useful and is especially adapted for use in connection with the cat head of a well drilling apparatus, it is to be distinctly understood that I do not intend that it be limited to such use, for in its general application it may be used in connection with any apparatus where it is desirable to automatically stop any form of machinery in order to prevent accidents. And not only may such machinery be brought

to a stop automatically, but the same may be effected manually at any convenient distance from such machinery.

It is therefore an object of my invention to provide a novel form of apparatus whereby a moving mechanism or sets of moving mechanisms may be stopped practically instantly and automatically, or manually, at any convenient distance from such mechanism or mechanisms.

The above and further objects and advantages of my invention as will hereinafter more fully appear, I attain by the mechanism described in the specification and illustrated in the drawings, forming a part of my application.

Reference is had to the accompanying drawings, in which similar reference characters denote similar parts. In the drawings,

Fig. 1 is a plan view showing my apparatus applied to the two rotary cat heads of a well drilling apparatus and the motor for operating the same,

Fig. 2 is an elevational view of the mechanism for bringing the reverse lever of a motor to a vertical or neutral position,

Fig. 3 is a top plan view of Fig. 2, the reverse lever being shown in section,

Fig. 4 is a fragmentary cross sectional view of a motor cylinder, showing the position that the valve associated with said cylinder takes when said motor has been stopped.

Fig. 5 is an enlarged fragmentary detail top view of Fig. 1 showing my improved lever mechanism in the position in full lines that it assumes in relation to the rope wound on said cat head when it is wound evenly and in dotted position when said rope has become fouled or looped.

Fig. 6 is a detail view of the guiding member for guiding and steadyng the cables associated with my apparatus,

Fig. 7 is a longitudinal sectional view on the line 7—7 Fig. 6,

Fig. 8 is a cross sectional view of Fig. 5 on the line 8—8 and

Fig. 9 is a fragmentary detail cross sectional view on the line 9—9, Fig. 3.

Describing my invention more in detail, I provide a pair of standards or uprights 1,

each equipped with a supporting plate 2, which plates form a means whereby said uprights or standards may be positioned on the base or frame F of an engine or motor E, 5 said plates 2 being either integral with or secured to said standards or uprights as desired. In the form shown in Figs. 1 and 2, the uprights 1 are positioned on the frame F by removing the bolts 13 associated with 10 said frame and inserting them through suitable holes or slots formed in the plates 2. It is of course to be understood that if desired said uprights may be positioned on the main bearings M, shown in Fig. 1, of the 15 engine or motor E, or indeed in any other position found desirable, a suitable link or lever mechanism, or a set of cables, being supplied to operate the reverse lever R of said engine or motor. In the form shown in 20 Figs. 1 and 2 such additional link or lever mechanism or cables, are of course, unnecessary.

As shown in Fig. 1, 3 indicates the two cat heads that are associated with the draw works of the well drilling apparatus, said cat heads being mounted on and rotated by means of the cat head shaft, 8, which in turn is adapted to be rotated by means of a suitable transmission mechanism associated with 30 the main shaft of the engine or motor E. As shown in Figs. 5 and 8, the rope 31, used in connection with the cat head 3, is wound about said cat head. So long as said rope is wound evenly on said cat head as the shaft 8 thereof turns in the inclined bearing B, the lever 5, pivoted on the support 29, is in the position shown in full lines in Fig. 5, and no danger attends such a proceeding. Since the cat heads are being rotated at a very 40 rapid rate it frequently happens that the rope 31 becomes fouled or looped or crossed, which is a source of great danger to the operator or individual standing close by, said fouled rope often enveloping said operator or individual with sometimes fatal results. When this happens the rope 31 will cause the 45 lever 5 to assume the position shown in dotted lines in Fig. 5, the lever in such position coacting with the mechanism herein- 50 after more fully described, to bring the motor or engine E, as well as the fouled cat head 3, to practically an instant stop.

As shown in Figs. 5 and 8, the inclined bearing B is provided with a pair of bolts 55 42 and 43. I use said bolts to secure the support 29 to said bearings. In practice the distance between said bolts varies so that in addition to the hole provided in the support 29 to accommodate the bolt 43 I provide a slot 32 to accommodate the bolt 42, so that said support 29 may be applied to any bearing irrespective of the distance between said bolts.

The support 29 may also be provided with 60 a series of holes so that the pivot bolt 28

may be positioned in any one of them to provide for the proper mounting of the lever 5 in relation to the cat head 3. The support 29, as shown in Figs. 5 and 8, comprises an angular member bent at any convenient angle so that said support may provide for a proper position of the lever 5 in relation to the bearing B and the cat head 3.

70

Preferably, the lever 5 is pivoted to the support 29 in such a position that one arm thereof is positioned in close proximity with the inner end of the cat head 3. The two arms of said lever are arranged at an angle of about 120 degrees, though the number of degrees is not essential, provided the arms 80 of said lever will function as hereinafter more fully explained.

75

The arm of the lever 5 which is nearest to the cat head 3 is bifurcated, and has positioned thereon in any suitable manner a 85 roller 27, which roller provides an anti-friction means to prevent wear on the rope 31.

As long as the rope or line 31 is wound evenly on the cat head 3, the trip lever 5 remains unaffected. Should however said 90 rope or line become fouled, the lever 5 will be instantly actuated, the rope or line in this case piling up on the inner end of cat head 3, and as shown in Fig. 5, said lever will assume the dotted position shown in said figure 95 and pull the cable securely thereto, which cable, through the apparatus hereinafter more fully described, will actuate the reverse lever R of the engine E, practically 100 instantly bringing said engine, and consequently said cat head, to an abrupt standstill.

100

As shown in Figs. 5 and 8, I have provided a means whereby the trip lever 5 may be adjusted in relation to the cat head 3. 105 For this purpose I provide the support 29 with an upstanding lug 33, which lug has positioned therein an adjustable screw bolt 30. It is clear, however, that any other means for adjusting the lever 5 may be substituted for the construction shown.

110

As shown in Fig. 1, there are two such trip levers 5 provided, one for each cat head 3, said levers each having associated therewith a cable 4, the length of which may be adjusted by means of the turnbuckles t. While I have shown said trip lever applied to the cat head of the draw works of a drilling apparatus, it is clear that I do not desire to be limited to such a feature, but may place such trip levers in any other position found in practice to be desirable, and may associate the same with any rotary member or other mechanism which it is desired to stop practically 120 instantly in order to avoid accidents or for other reasons.

115

Reference is now had to Fig. 4. To bring the motor or engine E to practically a sudden stop, the valve v controlling the ports to the cylinder C must be brought to the position 125 130

shown in said figure; that is to say, the fluid pressure on both sides of the piston must be equalized. As shown in said figure communication is established between each side of the piston through the two outer ports and the valve chest, the port opening on each side of said valve being quite small. It is clear that this feature of my invention affords a quick and efficient means for holding the piston stationary and consequently insuring substantially the immediate stoppage of the engine. When the reverse lever R is in neutral position, as shown in dotted lines in Fig. 2, the valve v in Fig. 4, being open, is in the position shown in said figure.

Reference is now had to Figs. 2, 3, and 9. Said figures show the automatic means for bringing the reverse lever R of the engine or motor E into vertical or neutral position when the rope or line 31 on the cat head 3 has become fouled.

The standards or uprights 1 are preferably, though not necessarily, held in adjustable relation by means of one or more cross plates 6, there being in the present instance, as shown in Fig. 9, a pair of such plates, which cross plates are adapted to fit snugly into cut out portions provided in said uprights. Said plates are suitably secured in position by means of bolts or screws 15, or any other preferred means, one or more slots 7 being provided in either end for adjusting purposes.

To space the upper portion of the standards or uprights 1 properly, and for adjusting purposes, I use a pair of upper main guide bolts 19, and a pair of lower main guide bolts 20, which, as shown, are provided with suitable adjusting nuts so that the length of said bolts as well as the distance between said upright may be adjusted. The purpose of said bolts is also to provide a guiding and steady means for one or more reverse lever control members, to be presently described. It is of course to be understood that any other means for adjusting the distance between the uprights as well as for guiding and steady the reverse lever control member or members may be substituted for the construction just described.

The reverse lever control members 16 and 17 are shown in Figs. 2, 3, and 9, and are of identical construction and configuration, so that, if desired, they may be cast from the same pattern, or produced in any manner found desirable. Each of said members is provided with grooves, as shown more particularly in Fig. 9, in which the bolts 19 and 20 are adapted to take. In Fig. 9 the lower member complementary to the upper member 16, has been omitted for the sake of clearness. Of course, if desired the number of bolts and grooves used may be increased, or decreased, as found in practice to be desirable.

As shown, the reverse lever control members are adapted to be positioned in slideable

relation with each other. A portion of the length of each of said members is reduced in width, and they are preferably, though not necessarily, oblong or square in cross section, said reduced portions being preferably, though not necessarily, circular in cross section so that they may be easily manufactured and readily passed through the uprights 1. It is clear however that if desired the ends passing through the uprights may be square or oblong in cross section.

Preferably, though not necessarily, suitable bushings 38 are provided in the uprights 1 for the purpose of providing for wear, and against which bushings the springs 21, encircling the ends of said members are adapted to press. If desired also, the uprights 1 may be countersunk to provide a means for positioning said springs, each of which has a washer 39 for the other end of each of said springs, suitable nuts 40 being used to adjust the tension of said springs.

Each of the reverse lever control members is provided with a slot 18 to accommodate the reverse lever R, so that while said reverse lever is controlled by said members, said reverse lever may nevertheless be operated manually without interfering with the operation of said members.

To set the valve v in proper position in relation to the position of said reverse lever, I have provided the members 16 and 17 with adjustable bolt and lock nut means 22. Said means 22 provides for an accurate adjustment of said valve in relation to the reverse lever, so that when said reverse lever is in the dotted position shown in Fig. 2, the valve v shown in Fig. 4 will be in such a position as to stop the engine or motor substantially instantly.

To prevent the reverse lever control members from moving too far, the uprights 1 are provided with adjustable stop studs 44 and 45, so that the throw of said control members may be accurately adjusted so that the reverse lever R may be brought to a vertical or neutral position at the proper time.

Each of the reverse lever control members is provided with a triangular cam projection 24, either formed integral with said members, or secured thereto in any preferred manner, said cam projections being identical in size and shape, so that said reverse lever control members may be interchanged. Preferably, though not necessarily, said cam projections are positioned on the wider portions of said control members and at the point where said members are reduced in width. Of course, if desired, said cam projections may be placed in any position on said control members found to be desirable.

To provide an automatic mechanism for instantly releasing the cam projections 24, and in turn the members 16 and 17, I have po-

sitioned a pair of trip pawls P on the cross plate 6 in close proximity with the cam projections 24. Said pawls are pivoted to said cross plate by means of suitable screw bolts 5 or other means 26, said pawls being held in engagement and under spring tension, with the projections 24 by means of the springs 11, anchored to the uprights 1 and to the pawls P by suitable screw bolts or other means 14.

10 As seen in Figs. 2 and 3, the pawls P are preferably, though not necessarily, cut away as shown, so that they will be in overlapping engagement. Each end of said pawls is provided with a vertical portion, either integral 15 therewith or secured thereto in any preferred manner, the end portion of the pawl adapted to engage the cam projection 24 on the upper controlling member 16 being approximately of twice the length as the end portion adapted 20 to engage the cam projection on the lower member 17.

Should the valve v associated with the engine E become worn so that it will not be positioned properly to bring said engine to a 25 standstill when the reverse lever R is in the dotted position shown in Fig. 2, or should a single cylinder engine, provided with the usual fly wheel, be equipped with a leaky valve, or for some other reason said valve is 30 not positioned properly, it will be necessary to substitute for one of the pawls P another of shorter length so that the reverse lever R will be moved past its vertical position in order that the other pawl P may let go the 35 cam projection 24 with which it is in engagement, to bring said valve to the proper position to stop the engine instantly.

As will be seen from Fig. 2, the end portions of the pawls P as well as the cam projections 24, are beveled so that when said end portions release said cam projections, they 40 may readily pass each other. When the pawls P are in engagement with the projections 24, said pawls assume the position 45 shown in full lines in Fig. 2. In this position it is possible to manipulate the reverse lever R to reverse the engine or stop the same by placing said lever in neutral position, without in any way interfering with the 50 members 16 and 17. When the pawls P are out of engagement with the cam projections 24, they assume the dotted positions shown in said figure.

To operate the pawls P, either manually 55 or automatically, I have provided a pawl trip lever 9 pivoted to the cross plate 6 by means of a suitable bolt or other means 10. Said pawl trip lever is connected to either or both cat heads 3 by means of a cable or cables 4, which may be adjusted by the turn buckles t. It is of course clear that said pawl trip lever 60 may have its cable or cables 4 extended to any convenient point, and may be operated manually, and may not be connected to the cat heads 3 as just described. When either or

both of the cables 4 is pulled, either automatically or manually, the end portion 46 of said lever causes the pawls P to assume the position shown in dotted lines in Fig. 2, the trip pawl lever 9 also assuming the dotted position shown in said figure.

The members 16 and 17 being held under the compression of the springs 21, are caused by said springs to move suddenly away from each other when the lever 9 has caused the 75 pawls P to release the cam projections 24. The action of said members will accordingly bring the reverse lever R into neutral or vertical position, which in turn will bring the valve v into the position shown in Fig. 4, 80 practically instantly stopping the engine.

As shown on Fig. 2 the lever 9 may have associated therewith a suitable stop member 25 positioned on the cross plate 6, though this is not essential.

To provide a means for steadyng and guiding the movement of the cables 4, as well as to reduce any wear thereon to a minimum, I have equipped the standards or uprights 1 with a novel form of trip line guide 35, shown 90 in detail in Figs. 6 and 7. Said trip line guide is provided with a supporting means 37, either integral therewith or secured thereto in any preferred manner, said support being set at any convenient angle to the main portion of said guide. Said supporting means 37 is adapted to be secured to one of the uprights 1, in any preferred position, preferably though not necessarily, to the top thereof by 95 means of screws, bolts or the like.

The main portion of the trip guide 35 is preferably, though not necessarily, rectangular in cross section, and is provided with a pair of rollers 34, mounted on pintles 41, said rollers being held in position and spaced from each other by a pair of projections 36, as shown in Fig. 6. As will be clear from Figs. 6 and 7, the cables 4 pass between the rollers, which rollers act as a steadyng and guiding means as well as an anti-friction means for 100 reducing wear on said cables to a minimum.

In operation, the lever control mechanism shown in Fig. 2 is positioned on the engine frame F in the manner previously described, the reverse lever R being positioned in the slot 18. If the valve v is not positioned in proper relation to said reverse lever, for reasons hereinbefore mentioned, the bolts 22 are 105 adjusted so that said lever when brought to neutral or vertical position will cause said valve to occupy the position shown in Fig. 4. In view of the fact that the engines used in oil well practice vary in character, and that the valves encountered therein after considerable use become leaky, pawls of universal 110 size cannot be used. In such cases pawls of different length are substituted for the pawls P to provide for a proper and exact functioning of the control members 16 and 17.

This having been done, the throw of the 115

control members 16 and 17, or the distance through which said members are moved, is adjusted by means of the stop bolts 44 and 45, by screwing said bolts toward or away from the uprights 1, said members striking said bolts 44 and 45 at the proper distance so the lever R shall be placed in the dotted position shown in Fig. 2. The apparatus is now in the position shown in Figs. 2 and 3, as indicated by the full lines, and the engine E is in operation. The pawls P being in engagement with the cam projections 24, the control members 16 and 17 are held stationary and under the compression of the springs 21. It will be clear that the reverse lever R under these conditions will be free to be operated manually without in any way interfering with the apparatus described.

It will be understood, of course, that after the reverse lever R has been positioned as shown in dotted lines in Fig. 2, the members 16 and 17 and pawls P are set manually, as shown in full lines in said figure.

As long as the rope 31 on the cat head 3 is wound evenly the apparatus will remain inactive. The rope or line 31, pulling as it does at an angle, invariably fouls or crosses or loops at the inner end of the cat head where the lever mechanism 5 is positioned. Should said rope become fouled, the roller 27 of the lever mechanism 5 will instantly be pushed outward by said fouled rope, as indicated in dotted lines in Fig. 5. This action will cause the lever to swing substantially to the dotted position shown in said figure, giving a sharp pull on the cable 4. Said cable will accordingly pull the lever 9 to the dotted position shown in Fig. 2, its end 46 displacing the pawls P to their dotted position shown in said figure, and instantly release the cam projections 24. The control members 16 and 17, under the compression of the springs 21, will instantly fly out away from each other, insuring that the reverse lever R be brought to the dotted position shown in said figure. This action will bring the valve v into the position shown in Fig. 4, substantially instantly stopping the engine or motor E, and of course the rotation of the cat head 3. The movement of the cat head being stopped, it is clear that all danger from the fouled rope 31 will be instantly and effectively eliminated.

It is also clear, that the apparatus shown in Figs. 2 and 3 may be dispensed with entirely, so long as the valve v may be brought into the position shown in Fig. 4. Moreover, it is to be understood that my invention is not limited in its application to a rotary cat head merely, but is applicable to any rotary member or any mechanism in the operation of which there is any danger to bodily injury of the operator or any individual standing close by. My invention admits both of automatic or manual operation, it being within the province of my invention to posi-

tion cable or cables 4 in such a manner and in such a position that they may be operated either automatically or manually to bring the engine or motor E practically to an instant standstill.

While I have described my invention with great particularity, it is clear that the same may be modified throughout a wide range. I accordingly do not propose to be limited to the exact details of construction shown and described, but reserve the right in practice to make any and all modifications thereof that fall within the scope of the appended claims.

I claim as my invention:

1. In an apparatus of the class described including a steam engine provided with distributing valves and a reverse lever, of a rotary shaft, a cat head mounted on said shaft, a rope coiled about said cat head, a bearing in which said shaft is adapted to rotate, sets of means connected to said bearing and engaging said rope, which means, when said rope fouls on said cat head functions to bring said reverse lever to neutral position so that said engine will without extraneous assistance function as a brake to bring said cat head to a stand still substantially within a quarter of a revolution thereof.

2. In a safety apparatus including a motor to be stopped, the combination of a rotary shaft, a cat head mounted on said shaft, a rope coiled about said cat head, a bearing in which said shaft is adapted to rotate, mechanical means on said bearing adapted to be engaged by said rope when it fouls, and trip means on said motor connected to said mechanical means for causing said motor to function as a brake without extraneous assistance when said rope fouls on said cat head.

3. In a safety mechanism including a rotary motor having a reverse lever, the combination of a rotary shaft, a cat head mounted on said shaft, a rope coiled about said cat head, a bearing in which said shaft is adapted to rotate, adjustable means on said bearing for engaging said rope when it fouls, trip means adapted to actuate said reverse lever for bringing said lever to neutral position to cause said motor to act as a brake, and a connection between said trip means and said adjustable means, said connection being adapted to be operated manually to trip said trip means, or automatically when the rope on said cat head fouls.

4. In a safety device for a rotary cat head driven by a fluid pressure motor, the combination of a rotary shaft, a cat head mounted on said shaft, a rope coiled about said cat head, a bearing in which said shaft is adapted to rotate, a bell crank pivoted to said bearing, adapted to be engaged by said rope when it fouls, means for adjusting the throw of said bell crank with respect to said rope, and means connected to said bell crank, and

adapted to control said motor to cause said motor to function as a brake when said rope fouls.

5. In a rotary cat head safety device, in combination, a cat head about which a rope is adapted to be coiled, a bearing for said cat head, a plate adjustably mounted on said bearing, means for adjusting said plate relative to the bearing, a bell crank pivoted to said 10 plate, means on said plate for adjustably limiting the movement of said bell crank, anti-friction rope engaging means carried in one arm of said bell crank, and means connected to the other arm of said bell crank 15 whereby said cat head may be substantially instantly stopped when said rope fouls.

6. In a device of the class described, in combination, a rotary member, about which a rope is adapted to be coiled, means connected to said member whereby it may be rotated, a bearing in which said member is rotated, a movable member pivotally mounted on said bearing and detachable therefrom, and means on said movable member whereby 25 wear on said rope will be reduced to a minimum, when said movable member is actuated by said rope to bring said rotary member to substantially an instant standstill.

7. In an apparatus of the class described, 30 including a fluid pressure motor, the combination of a rotary cat head about which a rope is adapted to be coiled, a bearing in which said cat head is adapted to be rotated, a trip mechanism mounted on said bearing, 35 said trip mechanism being adapted to be tripped when said rope fouls, a second trip mechanism adapted to control said motor to bring the same substantially to an instant standstill, and an adjustable connection between both of said trip mechanisms which connection may also be manually operated to 40 actuate said second trip mechanism.

In testimony whereof I have signed my name to this specification.

45 ALFRED W. POSEY.
